UNITED STATES PATENT OFFICE.

EDWARD A. RIX, OF SAN FRANCISCO, CALIFORNIA.

METHOD OF COMPRESSING GAS AND APPARATUS THEREFOR.

Application filed July 13, 1922. Serial No. 574,622.

To all whom it may concern:

Be it known that I, EDWARD A. RIX, a citizen of the United States, residing at the city and county of San Francisco and State 5 of California, have invented new and useful Improvements in Methods of Compressing Gas and Apparatus Therefor, of which the following is a specification.

This invention relates to a method of 10 compressing gas and an apparatus therefor.

In oil fields where gas is tapped that is wet or carries gasoline in vapor form, it is common practice to employ a reducing valve and to permit the gas to escape under 15 a pressure of approximately 50 pounds gauge, this being true no matter how much in excess of this pressure a well may be capable of delivering the gas, the reason being that the petroleum production of the 20 well is least interfered with when the gas escaping is maintained at this pressure or less. The gas escaping or discharging from the well under approximately 50 pounds pressure gauge is delivered to a gas 25 compressor and is here boosted 300 pounds pressure gauge. It is then passed through cooling coils and absorbers to precipitate the gasoline vapor in the form of liquid gasoline and the gas thus relieved of the 30 vapor is delivered to mains and is conveyed through these mains in many instances several hundred miles to the larger cities where the gas is employed for industrial and public utility purposes. Formerly 35 large gas compressors were installed to compress the gas but it was found that when the wells were no longer productive that the expense of moving large plants of this character to other wells was burdensome and expensive, and as the result thereof a standard 40 gas compressing unit has come to be generally adopted. These standard gas compressing units consist of duplex belt driven compressors driven by 160 H. P. gas engines. Practice has determined that these 45 compressors should be equipped with two 8 inch diameter by 16 inch stroke single stage cylinders when the gas pressure delivered thereto is 50 pounds pressure gauge. Such 50 compressors operate at 150 R. P. M. and 300 pounds final pressure and they will approximate 1200 cubic feet of free gas and absorb all the power of 160 H. P. engines under such conditions.

55 As the pressure in the wells falls below 50 pounds pressure and on down to atmos-

pheric pressure, various combinations of larger diameter cylinders are placed on the compressors until when the gas pressure approximates 5 pounds intake pressure or less, 60 the compressors become two-stage compressors with 16 inch diameter low pressure cylinder and 8 inch diameter high pressure cylinder, the stroke remaining constant or 16 inches. It is found that when this combination of cylinders is employed that 560 cubic feet of free gas at 300 pounds pressure are delivered and that all the power of the gas engines is consumed.

The difference in the quantity of free gas 70 compressed between the extremes of 50 pounds pressure and zero or atmospheric pressure, to-wit, from 1200 to 560 cubic feet, represents the work done by the gas itself in entering the 8 inch diameter single stage 75 cylinders at 50 pounds pressure. Experience has also determined that much time is lost and a large expense is incurred in changing and providing the cylinders of varying size, and also in providing repair 80 parts for the cylinders of varying size. Experience has also determined that when the cycle of changes has been completed and the 16 x 8 x 16 two stage machine is finally developed that it has cost at least two prices 85 and that much loss in time and output has been encountered.

My invention involves a method of compressing the gas and an apparatus therefor, and it consists in installing the 16 x 8 x 16 90 two-stage cylinders immediately and equipping the low pressure cylinder with a variable pressure device or cut off mechanism which will enable all intake pressures from 50 pounds gauge to zero or atmospheric pressure to be delivered to the compressor, causing the compressor to discharge from 1200 to 560 cubic feet of free gas per minute at 300 pounds pressure and with a slightly less expenditure of power when comparison 95 is made with the old method just referred to. More specifically stated this is accomplished by feeding the discharging gas from the well to the inlet valves of the compressor through a suitable form of cut off 100 valve mechanism which may be best adapted to the purpose, thus making the low pressure cylinder an expansion engine on one side and a compressor on the other and alternating these cycles at each revolution.

One form of compressor or apparatus suitable for the method involved is illus-

trated in the accompanying drawing, in which the figure is a horizontal, longitudinal section of a two-stage compressor showing the low stage cylinder equipped with the 5 cut off valve mechanism whereby the volume of gas admitted during each suction stroke is regulated.

Referring to the drawing in detail, A and B indicate the low pressure and high 10 pressure cylinders, respectively, 3 the inlet valves in the respective cylinders, 4 the discharge valves, 5 the inlet air passage to the low pressure cylinder, 6 the inlet air passage to the high pressure cylinder, 7 the 15 discharge passage in the low pressure cylinder, 8 the discharge passage in the high pressure cylinder, and 9 an inter cooler of suitable construction which connects the discharge passage of the low pressure cylinder 20 with the inlet passage of the high pressure cylinder. Each cylinder is provided with a piston as indicated and these are in turn driven from a main driving shaft C by means of cranks, connecting rods, cross 25 heads and piston rods in the usual manner. The respective cylinders and the heads employed in connection with the same are water cooled in the usual manner and the shaft C is preferably driven by means of 30 a pulley and belt from 160 H. P. gas engine not here illustrated.

Forming an integral part of the low pressure cylinder or suitably secured thereto is a valve chest 10 in which are slidably 35 mounted the cut off valves, and slideable exterior thereof is the main valve 11. The cut off valves are indicated at 12, there being two employed, which are adapted to be moved to or away from each other by 40 means of a right and left hand threaded rod 13. This rod is turned by means of a hand wheel 14, which is connected to the valve rod by a sliding feather and slot, and employed in conjunction therewith is an index 45 mechanism 14^a, whereby the amount of cut off may be visibly indicated. The entire valve mechanism shown is in reality nothing more or less than a standard form of cut off valve, known as the Meyers cut off 50 valve. The main valve is a sleeve valve having ports formed therein adapted to align with seat ports 20 and this valve is reciprocated by an eccentric 15, which is connected with an eccentric rod 16. The cut 55 off valves are reciprocated by the cut off eccentric 17 and they are connected thereto by the cut off eccentric rod 18, the valve rod 13 being connected with the rod 18 by means of a ball and socket connection as 60 shown to permit turning movement to be imparted to the rod 13 by means of the hand wheel 14. The cut off valves are circular in cross section and are balanced, and require merely sufficient power during operation 65 to overcome their sliding friction. A

small leakage in a valve of this character makes comparatively little difference because the valves are disposed in the inlet passage. When the cut off valves are drawn close together the main valve ports are clear 70 and no obstruction is offered the main valve which is in communication with the inlet poppet valves, but as the cut off valves are separated with relation to each other they interfere or cut off the main valve openings 75 at predetermined points indicated on the scale or index 14^a, and the amount of gas admitted during each suction stroke is thus controlled.

It will be noted that the main valve has 80 inlet ports only and thus differs from the ordinary slide valve in a steam engine, which employs both inlet and exhaust ports. It will further be noted that this variable 85 cut off mechanism operates entirely independent of the compressor cylinder valves and as such has nothing to do with the normal functioning of the compressor cylinder, the function of the cut off valve mechanism being only that of controlling the amount 90 of gas admitted, or in other words preventing an excess volume or pressure which might overload the motor.

By calculation first, and then by experience, a suitable chart may be made which 95 will indicate the proper cut off for each 5 pounds drop of pressure in the incoming gas, that is the entire range between 50 pounds and atmospheric pressure. The operator by referring to this chart, and noting the pressure of the incoming gas, may in this manner set the cut off mechanism by means of the hand wheel until the proper adjustment is obtained and such regulation of the valve mechanism may take place 105 without stopping the compressor.

I give herewith a comparative set of calculations for both the old and the new systems, showing the power required in each cylinder and the work obtained from the 110 gas, and I have chosen the maximum conditions as to pressure and volume and in making these calculations the formulae for air 115 has been employed instead of gas, inasmuch as the results are nearly the same and air is a perfect gas, and also due to the fact that the formulae pertaining to the compression and expansion of air are more familiar to all. The old system heretofore referred to begins operation with two 8 inch diameter 120 16 inch stroke single stage cylinders having a piston speed of approximately 400 feet and employing an intake pressure of gas approximating 50 pounds gauge, and as a consequence thereof discharging said 125 gas at 300 pounds pressure. The power required to compress the gas is 220 H. P. and the work realized by the intake pressure of 50 pounds is 60 H. P. The difference, or 130 160 H. P., is that required to be furnished 135

by the gas engine and the quantity of free gas discharged from the compressor is under these conditions 1200 cubic feet.

In my system the operation starts with a two-stage $16\frac{1}{2} \times 8\frac{1}{2}$ 16 inch stroke compressor, the piston speed being 400 feet. The intake pressure of the gas on the low pressure cylinder is 50 pounds, and under this condition cut off by means of the valve mechanism will take place at $\frac{5}{16}$ of the stroke. This, in order to insure the same delivery and volume of gas that the two 8 inch cylinders require in the old system. The gas after being cut off at one-half stroke expands isothermally on account of the heated cylinder to $17\frac{1}{2}$ pounds gauge. The work realized by the gas thus admitted is 92 H. P. The gas is then compressed to approximately 100 pounds gauge, which requires 154 H. P. of work during the compression stroke. The difference between these amounts, or 62 H. P., is the net work in the low pressure cylinder which the gas engine has to supply. The gas discharging from the low pressure cylinder at approximately 100 pounds pressure enters the high pressure cylinder which is $8\frac{1}{2}$ inches in diameter and here exerts a working energy approximating 68 H. P. The work of compressing this gas requires 159 H. P. and the net work is the difference between these two sums, or 91 H. P., which the gas engine supplies.

The low pressure cylinder requires 62 H. P.
The high pressure cylinder requires 91 H. P.

Making a total of 153 H. P.

to deliver 1200 cubic feet of free gas at 300 pounds pressure. This amounts to a saving of 7 H. P., and also eliminates the changing of the cylinders when comparison is made with the old system of compression. It might be suggested throttling the intake from 50 pounds to zero would enable the two-stage to operate. This is true, but for a delivery of 560 cubic feet only, the work in the gas being entirely lost.

In compressing gas by my system, the 100 pounds intercooler pressure obtained will cause considerable gasoline to be precipitated or condensed and reduces the quantity of gas delivered by the high pressure cylinder by $4\frac{1}{2}$ cubic feet for each 55 pound condensed and as this is not compressed to 300 pounds pressure that much working energy is saved. I therefore estimate that with the two power savings mentioned above, that the total net saving of 60 power by my system will under the maximum condition of operation as cited, approximate 10 to 15 per cent. This saving will of course be gradually lessened as the 65 intake pressure drops. The cut off valve will be backed completely away from the

main valve ports, when the pressure reaches zero, when the low or atmospheric pressure is reached and will then be inoperative and the old and new systems will be identical as far as efficiency and capacity are concerned. 70 When this happens the eccentric rods may be removed and the main sleeve valve may or may not be pulled out of the valve box. The variable pressure or cut off mechanism may be constructed as an independent unit so as to be conveniently attached to any cylinder. There are no clearance losses involved and it is for this reason not necessary that the cut off valve mechanism be placed immediately on the cylinder or adjacent the same, and as the entire valve mechanism is counter-balanced, as far as the gases are concerned, it is obvious that only sufficient power to overcome the inertia and friction of the moving valves is all the 85 power required.

Having thus described my invention, what I claim and desire to secure by Letters Patent is—

1. In a compressor of the character described the combination with the inlet ports of the low pressure cylinder, of means for regulating the volume of gas under pressure admitted during a portion of each suction stroke. 90

2. In a compressing unit of the character described the combination with the inlet ports of the low pressure cylinder, of means connecting said inlet ports with a source of gas supply delivering gas under varying pressures, and means cooperating with said delivering means for controlling the volume of gas delivered to the low pressure cylinder during each suction stroke. 100

3. In a compressing unit of the character described the combination with the inlet ports of the low pressure cylinder, of means connecting said inlet ports with a source of gas supply delivering gas under varying pressures, and means cooperating with said delivering means controlling the volume of gas delivered to the low pressure cylinder during each suction stroke, said means being adjustable to deliver varying volumes of gas. 105

4. In a compressing unit of the character described a low pressure compressing cylinder and a cut off valve cooperating therewith adapted to regulate the volume of gas admitted during each suction stroke. 115

5. In a compressing unit of the character described a low pressure compressing cylinder and a cut off valve cooperating therewith adapted to regulate the volume of gas admitted during each suction stroke, said cut off valve being adjustable to vary the volume of gas admitted during each suction stroke. 125

6. A method of compressing gas delivered to a compressor under pressure, which con- 130

sists in regulating the volume of gas admitted during each suction stroke of the compressor and then compressing the gas thus admitted.

5. A method of compressing gas delivered to a compressor under pressure, which consists in admitting the gas during a portion of the suction stroke of the compressor, permitting the gas thus admitted to exert its 10 expanding force during the remaining portion of the stroke, and then compressing the gas during the return stroke.

8. A method of compressing gas delivered to a compressor under pressure, which consists in admitting the gas during a portion 15 of the suction stroke of the compressor, permitting the gas thus admitted to exert its expanding force during the remaining portion of the stroke, compressing the gas during the return stroke and then discharging the gas during said stroke at a higher pressure than that under which it was admitted during the suction stroke.

EDWARD A. RIX.
